United States Patent

Des. 236,919
Patented Sept. 23, 1975

236,919

BOTTLE FOR MEDICAL LIQUID

Charles J. McPhee, Sylmar, Calif., assignor to American Hospital Supply Corporation, Evanston, Ill.

Filed Feb. 26, 1974, Ser. No. 445,847

Term of patent 14 years

Int. Cl. D24—99

U.S. Cl. D83—1 U

FIG. 1.

FIG. 2.

FIG. 3.

FIG. 4.

FIG. 1 is a top plan view of a bottle for medical liquid showing my new design;

FIG. 2 is a front elevational view thereof;

FIG. 3 is a right side elevational view thereof; and

FIG. 4 is a bottom plan view of FIG. 2.

I claim:

The ornamental design for a bottle for medical liquid, as shown.
